SYSTEM FOR HANDLING AN EMULSION

Antum E. Cuthrell, Crowley, La.

Application June 17, 1938, Serial No. 214,209

2 Claims. (Cl. 196—3)

The present invention is directed to a positive displacement fluid pump to be operated on the principle of displacement of liquid by gases.

The principal object of the present invention is the provision of a simple, automatic, inexpensive pump to be used for the pumping of liquids where a liquid head is available and high pressure gas can be provided. In the particular embodiment hereinafter described the pump of the present invention is shown applied to oil well operation. It is apparent, however, that the pump is of general utility and is especially adapted for use as a sump-pump for sewage disposal and for the transfer of any liquid from a reservoir in which there is a liquid head to a different location.

In the accompanying drawing, Figure 1 shows the pump of the present invention schematically in an arrangement employed at oil wells for treating emulsions of oil-in-water.

Figure 2 shows the pump of the present invention in diagrammatic form in a borehole in which it is employed to pump oil to the surface.

In the production of oil a great deal of water is also produced, usually in the form of a water-in-oil emulsion. Before the oil is fed into pipe lines, it becomes necessary to break this emulsion. This is usually accomplished by treating the emulsion with a so-called demulsifying agent which separates the oil from the emulsion. This demulsifying operation is usually carried out at an elevated temperature so that the conventional apparatus employed for this operation is a separating tank, a heater and a pump for circulating the fluid from the heater into the separating tank. The emulsion is ordinarily fed into the separating tank by a tube known as the gun barrel.

In Figure 1 the separating tank is designated by numeral 1. A gun-barrel 2 is arranged in the tank so as to discharge the emulsion near the bottom of the tank, this gun-barrel being provided with a connection near its top with the tubing from the oil well. Pipe line oil is drawn off from the separator by line 3. An outlet pipe 4 is connected to the bottom of the tank and also to a heating coil, not shown, arranged in heater 5, said coil having an outlet pipe 6 which is provided with a flap valve 7 at a point just prior to its connection with a tank 8. Flap valve 7 is so constructed as to permit the flow of liquid through pipe 6 only into tank 8. On the opposite side of the bottom of tank 8 is an outlet pipe 9 provided with a flap valve 10. The other end 55 of pipe 9 is connected to the gun-barrel 2 above

the separating tank. The flap valve 10 is so constructed that the flow of fluid through pipe line 9 can take place only from tank 8 to the gun-barrel.

Tank 8 is a closed chamber provided at its top with a packing gland 11 in which is arranged a rod 12 which extends into tank 8 to a point near its bottom. The upper end of rod 12 outside of tank 8 extends into a small chamber 13 which is connected to tank 8 by a pipe 14. Chamber 13 is provided with an inlet pipe 15 connected to a source of high pressure gas, (not shown), and an outlet pipe 16 for gas. Carried by the rod 12 and arranged in the chamber 13 are a pair of pistons 17 and 18 which are spaced apart a distance greater than the distance between pipes 15 and 16, and so related to each other that when piston 17 covers outlet 16, piston 18 is above inlet 15, and when piston 18 covers inlet 15, piston 17 is below outlet 16. Arranged in chamber 8 is a float 19 provided with a central passage 20 which is adapted to encircle the rod 12, whereby the float 19 is guided by the rod 12 but can float freely with respect thereto. Near the upper end of chamber 8 rod 12 is provided with a stop 21, and near the lower end of chamber 8 it is provided with a stop 22.

The operation of the arrangement shown in Figure 1 is simple and automatic. An emulsion is fed into the separating tank 1 by gun-barrel 2 at a rate such as to keep a head even with outlet pipe 3. In practice, the demulsifying agent is usually fed in with the oil or added directly to the tank. The outlet valve on outlet 3 can be kept in closed position until a layer of pipe line oil collects in separating vessel 1. This layer will not be disturbed by the circulation in the arrangement shown. As can be seen from the drawing, the head of liquid in tank 1 is higher than the head of liquid in tank 8 and will be continuously maintained so.

With the parts in the position shown in the drawing, the tank 8 is filled with liquid and the float 19 has just actuated the rod 12 so as to move piston 18 off the inlet opening 15 and to move piston 17 onto the outlet 16. High pressure gas is, therefore, let into chamber 8 through inlet pipe 15 and connection 14, forcing the liquid in chamber 8 out through pipe 9 into the gun-barrel. When the liquid level drops to the point where the float 19 rests on stop 22, the weight of the float carries the pistons 17 and 18, which are normally held in any given position by friction, down to a position where the outlet pipe 16 is opened and the inlet pipe 15 is closed. This 55

permits the head of liquid in chamber 1 to force liquid through pipe 4 and pipe 6 through flap valve 7 into chamber 8, lifting the float 19 which follows the level of liquid until it contacts the stop 21 and again operates the pistons so as to permit the introduction of high pressure gas in chamber 8 and start the cycle again. It is to be noted that flap valve 10 does not open when flap valve 7 opens to admit liquid into chamber 8 because of the head of liquid in pipe 9 over flap valve 10.

Once the pumping is started and a layer of pipe line oil is established in separator 1, the operation is automatic and pipe line oil can be drawn continuously from separator 1. It is apparent that more than one tank 8 can be employed and operated in such a phase relation that the operation is continuous. For example, with a second tank 8, the line 6 will be branched and line 9 will be branched to have a connection with each tank, and the floats will be so regulated that one tank is exhausting gas while the other tank is exhausting liquid. Alternatively, a plurality of tanks 8 can be employed to operate in unison so as to increase the capacity of the unit.

In the arrangement shown in Figure 2, numeral 23 designates the casing in an oil well, and numeral 24 designates the tubing which conducts the oil to the surface. The tubing is of such a length as to extend well below the head of oil in the casing which is indicated for illustrative purposes as a dotted line 25. A flap valve 26 is arranged in the lower end of the tubing in such a manner as to permit the flow of fluid only upward through the tubing.

A chamber 27 is secured to the tubing by a threaded connection at its upper end, or in any other fashion, in such a manner that the lower end of the tubing extends nearly to the bottom of the chamber. Mounted on the top end of the chamber 27 is a packing gland 28 in which rides a rod 29 which is shown to be offset so as to lie close to the side of the chamber throughout its length. Secured to the lower end of the rod near the bottom of the chamber is a disc 30 perforated to embrace tubing 24. A similar disc 31 is fixed to rod 29 near the top of chamber 27. The upper end of rod 29 outside of chamber 27 extends into a small chamber 32 which is provided at its upper end with an inlet pipe 33 and at its lower end with an outlet pipe 34. Intermediate these pipes is a second outlet pipe 35 connecting chamber 32 to the upper end of chamber 27. Carried by rod 29 are a pair of pistons 36 and 37 respectively adapted to ride in chamber 32 and cover the entrances to pipes 33 and 34 respectively.

A float 38 is arranged in chamber 27 and is of such a form as to encircle tubing 26. This float is adapted to cooperate with stops 30 and 31 to actuate the pistons 36 and 37. The lower end of chamber 27 is provided with a flap valve 39 so arranged as to permit the flow of fluid only from the casing into chamber 27.

The operation of the arrangement shown in Figure 2 is much the same as that shown in Figure 1. With the parts in the position shown, the chamber 27 is filled with liquid and float 70 38 has just actuated pistons 36 and 37 so as

to cover outlet pipe 34 and uncover inlet pipe 33 which is connected with a source of high pressure gas at the surface. If desired, inlet pipe 33 can terminate just above the liquid level in casing 23 and the free space above the liquid in casing 23 can be filled with high pressure gas. In this case, outlet pipe 34 must continue to the surface. High pressure gas flows into chamber 27 through pipes 33 and 35 forcing down the fluid in this chamber into tubing 24. When the liquid level becomes low enough for the float 38 to rest on stop 30, the weight of the float actuates the pistons so as to close inlet pipe 33 and open outlet pipe 34. When this happens, the liquid level in the casing causes flap valve 39 to open to permit the flow of fluid from the casing into chamber 27 until the float 38 again contacts stop 31 and again actuates the pistons to start the cycle over. During the flow of fluid from the casing into chamber 27, fluid is prevented from entering the tubing 24 by reason of the liquid level in the tubing over the flap valve 26.

It will be apparent that the specific embodiments described above are merely illustrative of the forms which the present invention can take. It is evident that any one of a number of commonly known types of valves can be substituted for the piston arrangement shown in the embodiments. One obvious alternative is the use of a rotating valve operated with a rod and pinion, the pinion being fixed on the shaft of the rotating valve and the rack being at the upper end of the rod 12 in Figure 1. Any number of alternatives will readily suggest themselves to one skilled in the art. Likewise, changes may be made in the relation of parts to each other and in the size of parts without departing from the principle of the invention.

It is to be understood, therefore, that the present invention is not limited to the specific forms herein illustrated and described, but contemplates any apparatus utilizing the principles of operation upon which the specific embodiments shown are based. In the appended claims it is intended to claim the present invention as broadly as the prior art permits.

I claim:

1. A system for handling an emulsion of oil and water comprising a reservoir for said emulsion, a chamber carrying a float arranged below said reservoir, a conduit connecting the bottom of said reservoir with said chamber, a heater in said conduit, a source of high pressure gas connected to the upper end of said chamber, a valve mechanism controlled by said float adapted to control the feed of gas to said chamber in such a way as to admit gas into said chamber when the liquid therein reaches a predetermined height and to shut off the supply of gas when the liquid in said chamber drops to a predetermined level, a conduit for returning fluid from said chamber to said reservoir and an outlet for oil arranged adjacent the top of said reservoir.

2. A system, according to the preceding claim, in which the conduit for returning fluid from the chamber to the reservoir delivers the fluid at a point adjacent the bottom of the reservoir.

ANTUM E. CUTHRELL. 70
